UNITED STATES PATENT OFFICE.

JOHN F. DODGE, OF DETROIT, AND HORACE E. DODGE, OF GROSSE POINTE, MICHIGAN,
ASSIGNORS TO DODGE BROTHERS, OF DETROIT, MICHIGAN, A CORPORATION OF
MICHIGAN.

MOTOR-SUPPORT.

1,190,270.

Specification of Letters Patent. Patented July 11, 1916.

Application filed January 16, 1915. Serial No. 2,562.

To all whom it may concern:

Be it known that we, JOHN F. DODGE and HORACE E. DODGE, citizens of the United States, residing at Detroit, Michigan, and 5 Grosse Pointe, Michigan, respectively, have invented certain new and useful Improvements in Motor-Supports, of which the following is a clear, full, and exact description.

This invention relates to improvements in 10 motor supports, particularly adapted for supporting the front end of the casing which carries the motor, upon the frame of an auto car or the like.

An object of the invention is to provide 15 means which so connect said parts that it takes care of any variation in the dimension or distance between the front cross member of said frame and the holes in the frame through which the rear arms of the motor 20 are bolted.

Another object is to prevent the torque 25 of the frame from putting any strain upon the motor, whereby the frame may distort on the road without producing friction in the bearings.

Another object of the invention is to provide means having objects such as stated, adapted to permit the insertion and the removal of a starting crank so that the motor 30 can be cranked by hand.

Other objects are to provide a practical, efficient and strong motor support.

These being among the objects of the present invention, the same consists of certain 35 features of construction and combinations of parts to be hereinafter described and then claimed with reference to the accompanying drawings illustrating a suitable embodiment of the invention, in which—

40 Figure 1 is a sectional side elevation of so much of an auto car as will illustrate the present invention; Fig. 2 is a similar section, more fully illustrating parts shown in Fig. 1, specifically the bearing sleeve at the 45 forward end of the gear case and a portion of the pan below; Fig. 3 is a front elevation, specifically of the gear case and pan, showing how they are assembled; Fig. 4 is a front elevation, specifically of the cross member 50 of the frame, showing a part of the ball and socket connection; Fig. 5 is an enlarged transverse section on the line 5—5 Fig. 1; and Fig. 6 is a perspective view of the ball member.

*55 Referring to the drawings, a portion 10

of a frame, as for an auto car, is illustrated together with its front cross member or piece 11. There is also shown a portion 12 of the cylinder casting or block together with a portion 13 of the front gear cover, which together with other well-known parts constitute a support for the motor, not shown. It is desired under the present invention to provide a movable joint between the casing 12, 13 and the cross piece 11 of the car 60 frame. With this end in view, the construction illustrated is preferably used. The cross piece 11 is provided with a forwardly extending socket section 14 which is open at its front end. Said socket section may be 65 formed by striking up a suitable part of the metallic cross piece 11, so that said socket section 14 is integral with said cross piece but it is preferably formed as a separate annular part, as shown. An opposing socket 70 section 15 of annular form is provided, and this may be a separate part, which has a peripheral flange 16 placed against the inner side of the cross piece 11 and connected therewith, by means of removable 75 through bolts 17 as shown more clearly in Figs. 4 and 5. If the part 14 is a separate part, said bolts also pass through that. The part 15 may, however, be made integral with said cross-piece, it being struck up therefrom, instead of part 14. Said socket sections 14 and 15 constitute a socket or socket member. 80

The front end of the casing 12, 13 is provided with a cylindrical bearing sleeve 18 90 for receiving the tubular portion 19 of a ball member, which is provided with a ball shaped or spherical head 20, said tubular portion 19 having a snug fit in the bearing sleeve 18 and a sliding connection therewith. The ball head 20 is received and has bearing in the socket member 14, 15, so that the cross-piece 11 and the supporting casing of the motor are united by a movable joint, 95 preferably involving a ball and socket joint 100 as described.

The ball member 19, 20, is preferably made of seamless steel tubing, so shaped as to provide a hollow ball head 20. The tubular portion 19 thereof is preferably beyond the forward end of the crank-shaft 21 which is driven from the motor, the same being provided at its extremity with an engageable part such as cross-pin 21^a, so that a starting crank may be applied thereto. 110

- The spherical or ball head 20 is provided with a screw-threaded front opening 22 into which may be screwed a suitable cap or cover 23, for closing said opening, said cap 5 having a wrench receiving socket 23'. On removing the said cover a suitable starting crank may be applied to the forward end of the crank-shaft so that the motor may be started by hand if desired.
- 10 A preferably aluminum oil pan 24 is secured to the lower part of the casing 12, 13, the same being provided at its front end with a lip 25 adapted to fit against the outer surface of the tubular part 19 and into a 15 corresponding recess 26 at the under side of the forward end of bearing sleeve 18, so that oil leakage at this point is prevented.
- It is obvious that under the present invention any distortions of the frame 10 and 20 cross piece 11 are not transmitted to the parts which support the motor, and that the parts are so arranged and combined that an electric starter may be used or a hand-crank may be applied to the crank-shaft.
- 25 It is clear that when a hand-crank is used it may have a portion which bears within the tubular part 19.
- Not only does the construction hereinabove described provide effective motor supporting means, which will permit the desired relative movements of the motor and vehicle frame to prevent the distortions of the frame, in traveling over rough roads, from being transmitted to the motor, but 30 the construction described facilitates both the assembling of the machine and the removal of the motor from the machine. From an inspection of Fig. 1 of the drawings it will be seen that in disconnecting the 35 motor casing 24 from the cross bar 11, all that is necessary is to disconnect the front socket section 14, when the ball 20 and its tubular neck portion 19 may be withdrawn through the cross-bar 11 without any preliminary movement of the motor casing.
- An important feature of the invention is that substantially all of the parts of the connection, that is, the cross-bar 11, the ball 20 and extension 19, and the socket members 40 14 and 15 may be stamped and punched into substantially final shape, the whole connection requiring very little machining. Moreover, it will be noted that when assembled, the cross-bar 11 integrally surrounds the ball 20, and the slideway or sleeve 18 of the casing integrally surrounds the neck 19 or tubular radial extension of the ball. This provides a very strong support.
- This invention is susceptible of modification 45 as parts may be omitted, parts added and parts substituted without departing from the scope of the invention as expressed in the claims.
- What we claim as new is:—
- 60 1. In a motor support, the combination
- of two supporting members, a socket member carried by one of said members, a ball member comprising a cylindrical tubular portion and a hollow ball-head, said tubular portion being mounted on the other of said 70 two supporting members, and said head having a bearing in said socket and provided with an outward opening, and a closure for said opening carried by said head and having a wrench-receiving socket lying within 75 said opening.
2. In a motor support, the combination with a frame, a motor supporting casing, a motor driven crank shaft supported in said casing, and connections between said frame 80 and said casing comprising a socket carried by the frame, a ball having an integral tubular radial extension, said ball being received in said socket, said casing having a slideway in axial alignment with said crank 85 shaft in which said tube is received and guided, and said ball having an opening therethrough in line with said tube and said shaft.
3. In combination, a vehicle frame, a motor carrying frame, a motor crank shaft in said frame and a single connection between said frames at one end of said motor carrying frame, said connection comprising a universal joint in line with said crank shaft 90 and provided with a crank-receiving opening and a closure for said opening having a wrench-receiving socket extending into said opening.
4. In combination, a vehicle frame, a motor carrying frame, a motor crank shaft in said frame and a single connection between said frames at one end of said motor carrying frame, said connection comprising a universal joint having a longitudinal sliding 100 connection with one of said frames to provide for endwise relative movement of said frames, and said joint and sliding connection being in line with the motor crank shaft 105 and being provided with a crank receiving 110 opening.
5. In a motor-support, in combination, a vehicle frame comprising side bars and a cross-bar connecting said side-bars, a motor-carrying frame, a slideway in said motor-carrying frame, a ball socket on said cross-bar and opening upon opposite sides thereof, and a ball confined in said socket and having a rigid extension received in 115 said slideway.
6. In a motor-support, in combination, a vehicle frame comprising side bars and a cross-bar connecting said side-bars, a motor-carrying frame having a slideway, a ball socket on said cross bar and a ball confined 120 in said socket and having a rigid radial extension received in said slideway, said cross-bar integrally surrounding said ball and said slideway integrally surrounding said extension.

7. In a motor support, in combination, a vehicle frame comprising side-bars and a cross-bar connecting said side-bars, a motor-carrying frame, a horizontal slideway in said motor-carrying frame, and motor supporting connections between said motor-carrying frame and said cross-bar comprising a ball socket on said cross-bar and a ball confined in said socket and having a rigid 5 radial extension received in said slideway, said cross-bar surrounding said ball and constituting a portion of the ball confining means.

8. In a motor-support, in combination, a vehicle frame comprising a cross-bar, a motor-carrying frame having a slideway, a ball socket on said cross-bar, a ball confined in said socket and having a rigid radial extension received in said slideway, and a motor crank shaft in line with said slideway, said ball socket, ball and extension having crank receiving openings in line with said crank shaft.

9. A motor-support having, in combination, two supporting members out of supporting relation to each other and compensating supporting connections between said members whereby one is supported by the other, said connections comprising a ball and socket joint and a sliding connection between one of the parts of said ball and socket joint and one of said members, the bridging part of said connection being movable relatively to both members and removable through one of said members.

10. A motor-support having, in combination, two supporting members and compensating connections between said members, comprising a socket carried by one member 40 and a ball having an integral radial extension, the other member being provided with a slideway in which said extension is received and guided, and said socket having a removable ball-confining part so located 45 that said extension may be withdrawn from said slideway through said socket when said part is removed.

11. In combination, a vehicle frame, a motor carrying frame, a motor crank shaft in said motor-carrying frame, and a connection between said frames comprising a ball having an integral radial extension, a ball receiving socket in said vehicle frame, and a slideway for said extension in said motor frame, said ball and extension having a crank receiving opening in line with said crank shaft, and a closure for said opening carried by said ball.

12. In a motor-support, in combination, a vehicle frame, a motor-carrying frame and a connection between said frames comprising a ball having a radial extension rigid therewith, said motor-carrying frame having a slideway for said extension and said 65 vehicle frame comprising a cross-bar hav-

ing an opening which said bar integrally surrounds, means attached to said bar for completing a ball socket at said opening comprising a removable member arranged to permit the interruption of said connection by a movement of said ball and extension along the line of said slideway.

13. In a motor-support, in combination, a vehicle frame comprising side bars and a cross-bar, a motor carrying frame and a member for connecting said frames comprising a ball having a radial extension rigid therewith, said cross-bar integrally surrounding said member, a slideway for said tubular extension in said motor-carrying frame, and means attached to said cross-bar for completing a ball socket comprising a removable member on the side of said bar opposite to said motor frame, whereby said connecting member may be withdrawn from said slideway through said cross-bar.

14. In a motor-support, in combination, a vehicle frame comprising a cross-bar, a motor-carrying frame and a member for connecting said frames comprising a hollow ball having an integral, tubular, radial extension, said cross-bar integrally surrounding said member, a slideway for said extension in said motor-carrying frame, means attached to said cross-bar for completing a ball socket, said socket and said ball having upon the side opposite said extension registering openings, and a closure for said openings threaded into the ball opening and having a flange overlapping the sides of the 100 socket opening.

15. In a motor-support, in combination, a vehicle frame having a cross-bar, an opening in said cross-bar which said bar integrally surrounds, socket members upon 105 opposite sides of said bar at said opening, said socket members having registering openings upon opposite sides of said bar, a hollow ball having an integral, radial, tubular extension, said ball being confined in said socket and having an opening registering with one of the socket openings and its extension extending through the other socket opening, and a closure for said ball opening carried by said ball.

16. In a motor-support, in combination, a vehicle frame comprising a cross-bar, a motor-carrying frame and a member for connecting said frames comprising a hollow ball having an integral, tubular, radial extension, said cross-bar integrally surrounding said member, a slideway for said tubular extension in said motor-carrying frame, a motor crank shaft in line with said slideway, means attached to said cross-bar for completing a ball socket, said means and said ball having registering openings in line with said slideway, and a closure for said ball opening carried by said ball.

17. In a motor-support, in combination, a

vehicle frame, a motor-carrying frame, said vehicle frame comprising a cross-bar having a vertical web provided with an opening, stamped metal socket members attached to opposite sides of said web at said opening to form a ball-receiving socket, a ball and integral radial extension formed of seamless tubing, said motor carrying casing having a slideway for said extension and said ball being confined in said socket.

18. In a motor support, in combination, a vehicle frame, a motor-carrying frame, said vehicle frame comprising a cross-bar having a vertical web provided with an opening, a ball socket comprising a removable stamped metal socket member upon the side of said web remote from said vehicle frame, and a ball and integral radial extension formed of seamless tubing, said motor-carrying casing having a slideway for said extension, and said ball being confined in said socket.

19. In a device of the class described, a connecting member comprising a ball and integral cylindrical-tubular extension formed from seamless tubing, said ball having a threaded opening opposite the tubular extension, and a closure constructed to be screwed into said opening and having a portion thereof shaped to receive a wrench and also located within said opening.

20. In a motor support, the combination of two supporting members, a socket member carried by one of said members, a ball member comprising a tubular portion and a hollow ball-head, said tubular portion having a sliding connection with the other of said two supporting members, and said head having a bearing in said socket and provided with an outward opening, and a closure for said opening.

21. In a motor support, the combination of a frame having a cross-piece, a socket-section rigid with said cross-piece, a socket-side thereof, another, but annular, socket-section rigid on aforesaid socket-section; an opening upon the opposite side of said cross-piece, a motor casing provided with a bearing-sleeve which forms a supporting member, and means for uniting the latter and said cross-piece comprising a ball member having an extension sliding in said bearing-sleeve and the ball of which member bears in said socket.

22. In a motor support, the combination of a frame having a supporting member, a casing provided with a bearing-sleeve which forms a second supporting member, said sleeve having a recess at the lower side of its outer end, a pan at the bottom of said casing having a lip fitting said recess, and means for uniting said supporting members comprising a member loosely jointed to said first supporting member and having a sliding connection with said bearing-sleeve.

23. In a motor support, the combination

of a frame having a cross-piece, a motor-supporting casing, a motor-driven crank-shaft supported in said casing, a bearing-sleeve on said casing, a socket-member rigid with said cross-piece, a ball member comprising a tubular portion and a hollow ball-head, said tubular portion having a sliding connection with said bearing-sleeve and located in line with one end of said shaft, said head having a bearing in said socket and provided with an outward opening for receiving a crank to be engaged with said shaft.

24. In a motor support, the combination of a frame having a cross-piece, a motor-supporting casing, a motor-driven crank-shaft supported in said casing, a bearing-sleeve on said casing, a socket-member rigid with said cross-piece and comprising a socket-section located on said cross-piece and another, but annular, opposing socket-section rigid on aforesaid socket-section, a ball member comprising a tubular portion and a hollow ball-head, said tubular portion having a sliding connection with said bearing-sleeve and located in line with one end of said shaft, said head having a bearing in said socket and provided with an outward opening for receiving a crank to be engaged with said shaft.

25. In a motor support, the combination of a frame having a cross-piece, a motor-supporting casing, a motor-driven crank-shaft supported in said casing, a bearing-sleeve on said casing, a socket-member rigid with said cross-piece and comprising a socket-section located on said cross-piece, and another, but annular, opposing socket-section and provided with a flange, and removable bolts passing through said flange and cross-piece and said first socket section, a ball member comprising a tubular portion and a hollow ball-head, said tubular portion having a sliding connection with said bearing-sleeve and located in line with one end of said shaft, said head having a bearing in said socket and provided with an outward opening for receiving a crank to be engaged with said shaft.

26. In a motor support, the combination of a frame having a cross-piece, a motor-supporting casing, a motor-driven crank-shaft supported in said casing, a bearing-sleeve on said casing, a socket-member rigid with said cross-piece and comprising a socket-section located on said cross-piece, and another, but annular, opposing socket-section and provided with a flange, and removable bolts passing through said flange and cross-piece and said first socket section, a ball member comprising a tubular portion and a hollow ball-head, said tubular portion having a sliding connection with said bearing-sleeve and located in line with one end of said shaft, said head having a bearing in said socket and provided with an outward opening for receiving a crank to be engaged with said shaft.

opening for receiving a crank to be engaged with said shaft, the outer end of said bearing sleeve having a recess at its lower side, and a pan at the bottom of said casing having a lip fitting said recess.

27. In a motor-support, a vehicle frame comprising side-bars and a cross-bar connecting said side bars, a motor-carrying casing, a supporting connection between said 10 cross-bar and casing comprising a ball and socket joint and a horizontal sliding connection between one of the parts of said ball

and socket joint and said casing, said cross-bar integrally surrounding the ball member of said ball and socket joint, and said sliding 15 connection comprising a bearing of a length greater than the diameter of said ball.

Signed at Detroit, Mich., this 11 day of January, 1915.
